SELECTIVE LOADER FOR CARTRIDGE MACHINES

Filed Dec. 29, 1942

UNITED STATES PATENT OFFICE

2,402,195

SELECTIVE LOADER FOR CARTRIDGE MACHINES

John H. Woodberry and Frederick W. Hoe-
wischer, Metuchen, N. J.

Application December 29, 1942, Serial No. 470,428

6 Claims. (Cl. 86—45)

(Granted under the act of March 3, 1883, as
amended April 30, 1928; 370 O. G. 757)

1

The invention described herein may be manufactured and used by or for the Government for governmental purposes without the payment to us of any royalty thereon.

This invention relates to a mechanism for loading cartridges to a cartridge handling machine, such as a machine which inserts single cartridges into the pockets of a fabric belt, and more particularly, to a mechanism which loads the cartridges in the machine in a pre-selected manner or order. Belts and other cartridge containers usually hold four ball cartridges followed by a single tracer cartridge. It is the object of this invention to load cartridges to the belt-loading machine so that the said sequence ratio of ball and tracer cartridges will be maintained.

Cartridges, both ball and tracer, are packaged, as they come from cartridge making machines, in cardboard boxes containing twenty cartridges in double rows of ten each. It is a further object of this invention to provide a selective loader for a cartridge handling machine which will accommodate the said cartridge packages. That is, the improved selective loader of this invention will take a number of such standard cartridge packages, both ball cartridge packages and tracer cartridge packages, it being understood that the two types are packaged separately, and remove cartridges therefrom so that they are fed to the machine in the said pre-selected sequence of four ball and one tracer cartridges.

The improved selective loader is shown in the accompanying drawing as applied to the hand operated belt-loading machine of the Farr Patent No. 1,401,147 although it is clear that the invention may be applied to any type of cartridge handling machine. Fig. 1 is a top view of the Farr machine, corresponding to Fig. 1 of the patent, but also showing the improved selective loader in place.

Fig. 2 is an elevational view corresponding to Fig. 2 of the patent, and also showing the loader of Fig. 1.

Fig. 3 is a perspective view of the standard twenty round cartridge package.

Fig. 4 is a front elevational view of the improved selective loader in position as it is presented to the receiving magazine of the cartridge handle machine.

Fig. 5 is a fragmentary vertical section on line 5—5 of Fig. 1.

Fig. 6 is a fragmentary horizontal section on line 6—6 of Fig. 5.

The belt-loading machine about to be described has a magazine 61 which leads to the mecha-

nism of the machine generally designated 60 in Figs. 1 and 2 hereof. Magazine 61 holds a single vertical stack of cartridges 30, and has the cross-sectional outline shown in Fig. 6 presenting vertical guide ribs 63 which are received in the annular channel 33 of the cartridges 30. It is the function of the selective loader of the present invention to rapidly stack the cartridges (directly from their packages) in magazines 61 so that every fifth cartridge is a tracer. The standard twenty-round cartridge package, designated 20, shown in Fig. 3, contains two rows of ten cartridges each. Each cartridge is contained in a separate pocket defined by a centrally located separator 21 which extends to a point below the top edges of the box, see Fig. 3. It is understood that the box 20 is made sufficiently high so that its lid 23 just clears over the top of the cartridges. The separator board 21 is provided with nine narrower comb boards 22 placed transversely thereto so that twenty pockets are defined, ten on each side of separator 21. The lid 23 is secured in place by a label 24 which is pasted to the front of the box.

In order that the said standard package may be utilized in the improved selective loader of this invention, the top portion of the package must first be removed. Conveniently, the top portion may be cut at a point level with the top of the separator 21 and the combs 22. This point is designated 25 in Fig. 3. The top portion may be cut off in any convenient manner, by the use of knives, scissors or other appliances; or the package may be perforated peripherally at the level of point 25, or other removal or opening expedients might be employed.

The novel selective loader designated 10, see especially Fig. 4, is of sufficient size to snugly hold three standard cartridge packages designated B, B' and T in Fig. 4. Packages B and B' contain ball cartridges while package T contains tracer cartridges. It is readily seen from Fig. 4 that each vertical column contains six cartridges, the lower four being ball cartridges and the top two being tracer cartridges. The novel loader 10 with its load of three cartridge packages B, B' and T, is presented to the magazine 61 in the manner best shown in Fig. 2, that is with the said six-cartridge columns vertical and with the two ball cartridge packages below the single tracer package. The top of holder 10 designated 11 is provided with a flange 12 which extends over the top of the top row (horizontal) of cartridges. The top package always being tracer cartridges, flanges 12 will always be associated with a row

of tracer cartridges. It is thus seen that the function of flange 12 is to hold back the top row of tracer cartridges. As stated above, it is desired to stack the cartridges so that every fifth one is a tracer. Therefore the top row of the top package of tracer cartridges must not be emptied; only the lower five cartridges are removed, so that, as best seen in Fig. 5, the effective or removable vertical column will comprise four ball cartridges followed by a single tracer cartridge.

The package holder 10 is open at its front and at one of its ends and its top front edge has a downturned flange 12. At the open end of the holder and forming a continuation of its rear plate is a flaring lip 26, and there is a lip 27 on the side plate adjacent the rib 26, the lips cooperating to facilitate the entrance of the cartridge packages into the holder, and the removal of the empty or partially empty boxes from the holder. The cartridge box 20 is cut away along the line 25 so that when the filled boxes, minus their cut away portions, are placed in the holder the primer ends of the cartridges will extend beyond its edge in position to be presented to the magazine 61 with their grooves positioned to be engaged by the ribs 63 of the magazine, as shown best in Figure 6.

To feed a vertical column of four ball and one tracer cartridge to magazine 61, the holder 10, oriented as shown in Figs. 4 and 2, is presented to the magazine with its bottom resting on the top of the magazine (see the holder shown in dot-and-dash lines in Fig. 2), and the lowermost cartridge of the column brought into position to be engaged in the magazine (as shown best in Fig. 6) with the vertical ribs 63 of the magazine fitting in the annular channel 33 of the cartridge. This first movement of the holder is represented by arrow *a*, Fig. 2. The holder is then moved vertically downwardly (arrow *b*, Fig. 2) to engage the five cartridges of the vertical column. The top tracer cartridge is not to be fed into the magazine in any one operation of the holder and in order to limit the longitudinal movement of the holder with respect to the magazine so that this cartridge will remain in its package in the holder, I provide in the rear wall of the magazine 61 a shoulder 2 engaged by the flange 12 in the final longitudinal movement of the holder with relation to the magazine. Below the shoulder 2, the ribs on the magazine begin and the distance between the upper cartridge entry ends of the ribs and the shoulder is such that when the movement of the holder is arrested by engagement between the flange and shoulder, the top cartridge will be clear of the ribs and supported by the central partition 21 of the package 20 so that the holder can be freely moved laterally with respect to the magazine without disturbing the top row of cartridges in the top package. The arrangement of shoulder and ribs is in accordance with this invention and is an important deviation from the magazine structure disclosed in the Farr patent hereinbefore mentioned. The top of the magazine 61 may be provided with a beveled finger 3 to facilitate the positioning of the holder at the magazine.

After the five cartridges of a vertical column are engaged in the magazine, the holder is pulled away from the magazine (arrow *c*) to withdraw the three cartridge packages and all the cartridges except the said five of the engaged column. As the said five cartridges are left clear of their packages, they fall down the magazine to become stacked in the preselected order of four

ball followed by one tracer cartridge. For the next vertical column, the holder is moved vertically upwardly (arrow *d*) to original point A, and moved sidewise (to the left, as viewed in Fig. 4, arrow *e*) to present a fresh column to the magazine.

After all the ball cartridges in packages B and B' and the lower ten tracer cartridges of package T have been removed, the position of package T is reversed so that its top row is empty and its bottom row contains ten tracers. Two fresh packages B and B' of ball cartridges are placed in holder 10 in underlying relation to the half-filled package T of tracers.

We claim:

1. In combination with a belt loading magazine, a holder having a plurality of cartridges so grouped that a preselected series of cartridges may be fed to the magazine, said holder comprising a body adapted to envelope the cartridges while exposing the primer end thereof which is intended to be received in the magazine, said holder being intended for movement longitudinally of the magazine to feed the cartridges thereto, means carried by the magazine and means carried by the holder cooperating to limit the extent of longitudinal movement of the holder relative to the magazine to determine the number of cartridges delivered to the magazine from the holder in each single operation.

2. In combination with a belt loading magazine, a holder for holding a plurality of packages of cartridges in which the cartridges are so grouped that a preselected series of cartridges may be fed to the magazine, said holder comprising a body adapted to envelope a cartridge package while exposing the primer ends of the cartridges which are intended to be received in the magazine, said holder being intended for movement longitudinally of the magazine to feed the cartridges thereto, a downwardly extending flange carried by the holder, an abutment on the magazine engaged by said flange upon the movement of the holder, to limit the extent of longitudinal movement of the holder relative of the magazine to determine the number of cartridges delivered to the magazine from the holder in a single operation.

3. In combination with a belt loading magazine, a holder for holding a plurality of cartridges so grouped that a preselected series of cartridges may be fed to the magazine, said holder comprising a body adapted to envelope the cartridges while exposing the primer end thereof which is intended to be received in the magazine, said holder being intended for movement longitudinally of the magazine to feed the cartridges thereto, a downwardly extending flange carried by the holder, a shoulder on the magazine cooperating with the flange to limit the extent of longitudinal movement of the holder relative to the magazine to determine the number of cartridges delivered to the magazine from the holder in each single operation.

4. In combination with a belt loading magazine, a holder for holding a plurality of cartridges so grouped that a preselected series of cartridges may be fed to the magazine, said holder comprising a rectangular body open at one side and one end and adapted to receive a plurality of cartridge packages with the primer ends of the cartridges extending beyond the holder to be received in the magazine, said holder being intended for movement longitudinally of the magazine to feed the cartridges thereto, a downwardly

extending flange along the upper edge of said holder, and an abutment on the magazine engaged by the flange upon the movement of the holder to limit longitudinal movement of the holder relative to the magazine to determine the number of cartridges delivered to the magazine in a single operation.

5. In combination with a belt loading magazine having a shoulder adjacent its cartridge entry end and cartridge guide ribs whose cartridge entry ends are spaced from the shoulder, a holder for holding a plurality of pocketed cartridges so grouped that a preselected series of cartridges may be fed to the magazine, said holder comprising a body adapted to envelope the cartridges while exposing their primer ends intended to be received in the magazine, said holder being intended for movement longitudinally of the magazine to feed the cartridges thereinto, and a flange on the holder adapted to engage the shoulder on the magazine upon the movement of the holder to limit the longitudinal movement of the holder

10

15

20

with respect to the magazine, the shoulder and guiding ribs on the magazine being spaced for a distance slightly greater than the diameter of a cartridge so that the movement of the holder is arrested before the last cartridge in the holder reaches the guide ribs in the magazine.

6. A belt loading magazine having a shoulder adjacent its cartridge entry end and cartridge guide ribs spaced from said shoulder, said magazine being adapted for use with a cartridge container having a row of pocketed cartridges with their primer ends exposed and intended for longitudinal movement with respect to the magazine to feed the cartridges thereinto, the spacing between said shoulder and said cartridge entry end of the guide ribs being such that the longitudinal movement of the container will be arrested by the magazine shoulder before the last cartridge in the row reaches the said guide ribs.
